PROCESS OF IMPROVING THE SMOKING QUALITIES OF TOBACCO

Daniel Tyrer, Devon, England, and Denis D. Tyrer, College Park, Md.

No Drawing. Application January 31, 1955
Serial No. 487,462

2 Claims. (Cl. 131—140)

This invention relates to processes of improving the smoking qualities of tobaccos. The quality of tobacco depends upon many factors. In the broadest meaning of the term there is included aroma or smell (both of the tobacco itself and its smoke), color, texture, ashiness, combustibility, as well as strength or its opposite mildness. In the present invention we are concerned only with those factors which determine strength or mildness.

As is well known tobacco contains the alkaloid nicotine; and whilst nicotine is an essential ingredient of all tobaccos it is true that if a particular tobacco is relatively rich in nicotine that tobacco will be physiologically strong in smoking. But it does not necessarily follow from this that a tobacco low in nicotine is necessarily mild. Other factors besides nicotine are involved in the determination of the smoking quality of a tobacco.

It is generally agreed that flue-cured tobacco owes its distinctive quality largely to its high sugar content though other factors undoubtedly enter into the matter.

It is known that the mineral constituents play an important part in determining combustibility. In this respect potassium and magnesium are beneficial whilst chlorine is distinctly harmful.

But it is the nitrogen compounds present in all tobaccos which play the most important role in determining quality and tobacco technologists are generally agreed in ascribing "rankness" in a tobacco to a high protein content.

Now it will be generally agreed that in studying the problem of tobacco quality too much reliance cannot be placed on one's personal reaction in smoking. Whilst all smokers might agree in describing one particular tobacco as very strong or rank and another as very mild, opinions would differ about intermediate qualities. To get over this difficulty we have had resort to the chemical analysis of tobacco smoke rather than to the analysis of the tobacco itself. It is obvious that it is the smoke entering the smoker's mouth which determines whether a tobacco is mild and pleasing or strong and disagreeable.

In this connection tobacco technologists have noticed that the smoke of a bad quality tobacco has a relatively high alkaline reaction whereas a good tobacco gives a smoke of low alkalinity. The alkalinity of the smoke is due to ammonia, nicotine and other nitrogen bases derived from the nitrogen compounds in the tobacco which undergo pyrolysis during smoking. The pyrolysis of the nitrogen compounds has been the subject of experimental study by tobacco technologists particularly with reference to the fate of the nicotine content in cigarette smoking. (Incidentally it should be explained that the nicotine in tobacco is not present as the free base but exists in combination with acids and accordingly it is not simply vaporized during smoking.) In the case of cigarette smoking it has been found by one observer that about 20–25% of the nicotine in the tobacco enters the mouth partly as the free base and partly combined with acids in the smoke particles; about 50% is thermally destroyed while some 20% escapes into the air in the smoke rising from the burning tip of the cigarette whilst a few percent

2

are condensed in the stub. It should be mentioned, however, that other published data on this distribution of nicotine differ fairly widely from these figures. In tests we have carried out with pipe smoking it was found that 70–80% of the nicotine passes into the smoker's mouth.

Reverting to the question of how far the determinable alkalinity of the smoke can be taken as a reliable guide or index of tobacco quality we have endeavored to answer the question by purchasing a range of tobaccos, from the dearest to the cheapest, and relating the price to the smoke alkalinity as determined under standardized conditions.

The results are given in the following table. The smoke alkalinity (S.A.) is expressed in terms of cubic centimetres of N/10 acid required for neutralizing the free bases in the smoke from 1 gram of tobacco of a standard 12% moisture content. The table also gives the determined nicotine content of the tobacco reckoned on a dry basis.

Price of Tobacco, British currency, pence per oz.	Approximate U.S. Equivalent, cents per oz.	Nicotine Content, percent	Smoke Alkalinity (S.A.)
63	74	2.52	3.3
52	61	4.05	3.0
49.5	58	3.63	3.5
47	55	2.90	4.2
45.5	53	4.35	4.4
44	52	4.54	5.5
42.5	50	4.02	7.0
English grown, low qual.		0.90	9.8

Additional samples of tobacco were tested as set forth below:

Price of Tobacco	Nicotine Content, percent	Smoke Alkalinity (S.A.)
40 cents per 1½ oz.	1.79	3.9
30 cents per 1½ oz.	1.28	3.9
25 cents per 1½ oz.	1.33	4.8
15 cents per 1½ oz.	1.24	5.2
11 cents per 1½ oz.	1.35	7.0
Very low quality	1.65	11.4
Do.	2.07	12.2

The results given in the tables are the averages of a number of samples in each case. In addition to the purchased and branded tobaccos one sample of very poor quality, English grown and cured tobacco, is listed.

Taking the price as a measure of quality it will be seen that it bears no relationship to the nicotine content of the tobacco. This is brought out very clearly by the home-grown sample which contained only 0.90% of nicotine and yet proved to be very disagreeable to smoking.

On the other hand there is a clear parallelism between the price and the smoke alkalinity.

An exact parallelism could not, of course, be expected but it is definite enough to justify taking the smoke alkalinity as an approximate index of quality. This permits quality to be expressed by an experimental figure.

Research on the problem of improving the quality of tobacco thus became a matter of treating the material in various ways or of making various additions to it and then determining the effect on the smoke alkalinity.

Before detailing the results of special treatments it should be explained that the smoke alkalinity figures, as given in the above table, do not represent all the nitrogenous bases that occur in tobacco smoke. There is a minor quantity which is combined with organic acids (chiefly acetic and formic). These combined bases generally run closely parallel with the free bases but for the sake of completeness we have, in all our experiments, determined

both the smoke alkalinity and the total smoke bases which, in what follows, we indicate as T.S.B.

At this stage, also, it will be useful to give some account of what is already known in tobacco technology for improving the quality and at the same time checking the methods by smoke analyses. Such known treatments are as follows:

(1) Simple heating of tobacco is known to be beneficial and no doubt this is another reason why flue-cured tobacco is usually of good quality for in the flue-curing process the tobacco is heated to 90° C. or over. We have checked this procedure using air-cured tobacco. The following results are an example.

	S.A.	T.S.B.
Before heating.....	7.4	9.2
After 1 hour's heating at 100°.....	6.1	7.9

(2) It is known that the addition of some form of sugar to air-cured tobacco makes an appreciable improvement. Our own tests on the point show that the addition of sucrose has little or no effect (beyond a dilution effect) but that invert sugar is appreciably beneficial. Some results are as follows:

	S.A.	T.S.B.
Untreated tobacco.....	10.9	13.5
After incorporation 10% sucrose.....	10.0	11.0
After incorporation 10% invert. sug.....	8.5	10.6
After incorporation 15% invert. sug.....	8.4	10.4
After incorporation 20% invert. sug.....	8.3	10.3

(3) A good tobacco invariably shows an acidic reaction. Sometimes, however, a tobacco may have an unusually low acidity or, in the case of a fermented product, may actually be alkaline. In such cases an improvement is effected by incorporating a little acid. Hydrochloric acid to the extent of 1 or 2% has been suggested but with this particular acid there is a tendency for the combustibility to be unduly depressed.

The following experimental results indicate that acids in general have an ameliorating effect.

Tobacco and acid treatment	S.A.	T.S.B.
Untreated tobacco of low acidity.....	10.9	12.9
Same treated with 2% phosphoric.....	10.2	12.1
Same treated with 4% tartaric.....	8.9	11.0
Same treated with 3% glycolic.....	9.5	11.4
Same treated with 3.7% lactic.....	9.8	11.9

(4) A good deal of work has been done on reducing the nicotine content of tobacco presumably in the belief that a strong tobacco could be rendered mild and pleasing simply by removing the greater portion of the nicotine. This process of de-nicotinising has generally taken the form of subjecting the heated tobacco to a mixture of steam and ammonia when this latter base replaces some of the nicotine. One experimental example will illustrate the point. A very strong tobacco containing 5.15% nicotine and giving a S.A. of 10.9 was treated to reduce the nicotine to 2.1%. The S.A. of the product was 9.2—only a small reduction (considering the big drop in nicotine content) and still leaving the tobacco strong and unpleasant.

Our own researches on the problem have been directed towards the promotion of a greater degree of thermal destruction of the nitrogen bases during the combustion of tobacco during actual smoking, thus reducing the alkalinity of the smoke.

The results of our investigations are summarized as follows:

(1) *Primary catalysts.*—We have discovered that small additions of the salts of certain metals have a

marked catalytic effect. These, which we call primary catalysts, include salts of cobalt, manganese, nickel, copper, chromium and silver. Of these the salts of manganese and cobalt are the most effective.

5 The salts may be of almost any acid with certain reservations. Chlorides are effective but have the disadvantage of tending to spoil the combustibility though, if the tobacco is already too fast burning, this disadvantage disappears.

10 Generally, it is preferable for the salts to be soluble in water for then thorough incorporation into the tobacco is more easily effected. However, it is not impossible to use finely divided solids such as oxides and hydroxides, carbonates, phosphates. It has been found that the catalytic effect of the metal is enhanced when the acid associated with it is slightly volatile or can form a volatile acid on pyrolysis for then a part of the remaining nitrogen bases in the smoke are neutralized.

15 The one type of salt which appear to be definitely disadvantageous are sulphates. This is probably because they are reduced to sulphides which are not effective as catalysts.

20 The amount of catalyst required depends, to some extent, on the tobacco and on the degree of amelioration required. With some tobaccos 0.5% of the metal salt is sufficient but with others 2 or 3% is necessary to give a satisfactory result.

25 There is some evidence for a theory that sulphur compounds in the tobacco tend to poison the catalyst. (Tobaccos may contain as much as 1% of sulphur in the form of sulphates and organic sulphur compounds); and when the sulphur content is low a relatively small percentage of catalyst is satisfactory and vice versa.

30 (2) *Secondary catalysts.*—We have also discovered that certain other salts which, on general chemical grounds would not be expected to behave as catalysts, do in fact promote some decomposition of the nitrogen bases and in particular appear to increase the activity of the primary catalysts. These substances which we have 35 called secondary catalysts include salts of potassium, magnesium, barium and sodium—they are in this order of effectiveness.

35 A possible theory to explain their effect is that on heating they form strong bases which can fix some of the sulphur thus reducing the catalyst poisoning effect of this element. And the reason why they show some effect alone (i.e. without added primary catalysts) is that they permit the normal mineral matter of the ash of the tobacco to be more effective in decomposing the 40 nitrogen bases. (Tobacco ash contains appreciable amounts of manganese as well as much iron.)

45 As with the primary catalysts any salt of the above metals will serve (sulphate excepted) but those of organic acids are preferred. The amount to be used again 50 depends upon the tobacco and upon the extent of amelioration desired but in an average case 2% is satisfactory.

55 These secondary catalysts may be used alone but in general they are best used as promoters of the primary catalysts.

60 (3) *Acids.*—We have further discovered that both primary and secondary catalysts are more effective if the tobacco is appreciably acidic. Accordingly, when this 65 is not the case, it is advantageous to introduce with the catalysts a suitable proportion of an acid. Any acid except sulphuric will serve the purpose but the preferred acids are the simpler aliphatic acids as listed previously. Among inorganic acids phosphoric is satisfactory.

70 The amount of acid to be used may vary from 0-5% but generally 1% on the tobacco is satisfactory.

75 In the determination of the total smoke bases in our tests, the total smoke bases are expressed in terms of the number of milliliters of 0.1N acid required for their neutralization in the smoke resulting from the pyrolysis of one gram of tobacco.

Prior to a chemical analysis of the smoke, a "smoke

solution" is made by dissolving the products derived from the pyrolysis of tobacco in a known volume of 0.1N acid.

The total smoke bases consist of the free bases (smoke alkalinity) and the combined bases. In order to determine the total smoke bases it is necessary first to distil the smoke solution under alkaline conditions whereby the combined bases are released and are collected together with the free bases in an excess known volume of 0.1N acid. The distillate is then back-titrated with 0.1N NaOH to an end point of pH 5.9.

Calculation of the total smoke bases is as follows:

Let "x" represent the volume of 0.1N NaOH required in the titration, "y" the volume of acid added to the receiver in which the distillate is collected, and "w" the weight of tobacco used in the smoke test.

Then $y-x$ equals the volume of 0.1N acid required for neutralizing the total smoke bases derived from "w" grams of tobacco.

Therefore,

$$T.S.B. = \frac{y-x}{w} \text{ ml. per gram of tobacco}$$

(4) *Sugars.*—In the case of an air-cured tobacco which contains little or no natural sugar we have found that the addition of a suitable sugar enhances the effect of the catalysts. With flue-cured tobacco addition of sugar makes no difference.

The sugar used should be one rich in laevulose which appears to be more effective than dextrose and much superior to sucrose. As, however, a pure laevulose is not cheaply available there may be used, with satisfactory results, sugars consisting of a mixture of dextrose and laevulose such, for example, as invert sugar, uncrySTALLISABLE syrups, molasses, honey.

The amount used may be as much as 20% but we find 10% is generally adequate.

THE FINAL MIXTURE

Although individual catalytic substances may be used in particular cases the treatment in the general case will be with a mixture. The final mixture of substances to be used to give the highest amelioration depends upon the character of the tobacco to be treated. An initial analysis of the tobacco with respect to sugar content, nicotine content, total nitrogen, ash, would afford some guidance but only by a cumbersome method of trial and error could the optimum mixture be determined. A determination of the smoke alkalinity would provide some indication on the concentration of the catalyst mixture to be applied. However, it is possible to generalise and to give a formula which will serve in most cases. The recommended formula is 2% primary catalyst+2% secondary catalyst+1% free acid+8% invert sugar.

The percentages are on the tobacco and refer to the weights of the metal salts reckoned anhydrous.

In practically all cases the above general formula will give a considerable amelioration of a strong tobacco; in some cases it may be found that the tobacco has been rendered too mild in which case the simple remedy is to mix or blend some untreated tobacco with the treated product.

METHOD OF TREATMENT

As previously indicated it may sometimes be possible to apply the catalyst mixture as a fine powder when it can be dusted on the slightly moist tobacco as evenly as possible.

But in general it is more satisfactory to apply the mixture in the form of an aqueous solution (or sometimes as a suspension). In this form it may be applied either to uncut tobacco leaf or to cut and shredded tobacco.

If the treatment is applied to leaf the procedure is as follows:

The leaves should be just soft enough to be flattened out when they are sprayed with a solution of the mixture

to be applied the solution being up to about 40 parts by weight to 100 parts of the tobacco and containing the catalytic substances and any other substance it may be desired to apply either in a state of solution or as an aqueous suspension. They are then allowed to stand in a pile for several hours to allow the solution to soak in after which they are stripped (the midribs removed), pressed, cut and finally dried to the desired extent. The suitably dried product may be stored for ageing.

In applying the treatment to tobacco already cut and shredded the solution is sprayed on to a weighed quantity which is constantly stirred so as to spread the wetting as uniformly as possible. The solution and its concentration should be so adjusted that the final wet material does not contain more than 45% of water and preferably between 35 and 45%. After the spraying the moist material should be gathered into a ball or lump or otherwise pressed into a mass which is allowed to stand for several hours. The mass is then tested out and suitably dried. The drying is preferably done at a fairly low temperature. When dry it may be suitably heated as required and may finally be stored for ageing. If the tobacco was already heated and aged the treated product may be regarded as fit for immediate smoking.

Examples

(1) A heated and aged tobacco which had originally been air-cured, in cut and shredded form, was found to contain only 1.63% nicotine but was disagreeable on smoking. On testing the smoke it was found to be alkaline to an extent equivalent to 8.7 cc. of N/10 acid per gram of 12% moisture tobacco (S.A.) and to contain total smoke bases equivalent to 10.7 cc. of N/10 acid (T.S.B.).

100 parts of this tobacco were thoroughly moistened with a solution containing invert sugar and cobalt acetate in such amount as to incorporate into the tobacco 10% of the former and 2% of the latter, all quantities being calculated on a dry basis.

After drying the product gave smoke tests of 3.8 S.A. and 6.0 T.S.B. representing a degree of mildness which was found to conform with the personal reaction on smoking.

(2) A very strong, slightly alkaline, air-cured tobacco containing 5.5% of nicotine and giving smoke tests of 11.1 S.A. and 14.7 T.S.B. was wetted with a solution of invert sugar, phosphoric acid and manganese nitrate in such proportions as to incorporate into the tobacco 20% invert sugar, 2% phosphoric acid and 1.5% manganese nitrate. The dried product gave smoke tests of 5.7 S.A. and 7.7 T.S.B. and was found to be satisfactory on smoking.

(3) A freshly sun-cured tobacco in the form of leaf was sampled and found to contain 5.6% nicotine and to give smoke tests of 6.6 S.A. and 9.0 T.S.B. The nearly dry leaves were thoroughly sprayed with a solution containing potassium acetate, acetic acid and copper acetate, the proportions of the first two being such as to form potassium hydrogen acetate. The composition of the mixed solution and the amount used was such as was calculated to incorporate into the tobacco 2% of potassium acetate and 2% of copper acetate. After some hours standing the tobacco was stripped, pressed, cut and dried. The dry material was finally heated for 1 hour at 100° C. It was then tested and found to give smoke tests of 3.5 S.A. and 6.3 T.S.B. It was finally stored for ageing.

(4) The same tobacco was used as in Example 3 and the same procedure except that 2% cobalt acetate was incorporated instead of 2% copper acetate. The final product gave smoke tests of 1.4 S.A. and 5.1 T.S.B. This product was found to be too mild for enjoyable smoking and was accordingly mixed with an equal amount of the untreated tobacco. The mixture still showed the low smoke tests of 3.0 S.A. and 5.6 T.S.B.

(5) A strong tobacco which had been flue-cured contained 5.9% nicotine and gave smoke tests of 7.4 S.A. and 9.0 T.S.B.

Into it was incorporated 2% magnesium acetate, 1.6% acetic acid and 2% cobalt acetate. The product gave the very satisfactory smoke tests of 2.3 S.A. and 4.95 T.S.B.

(6) A solution containing 4 parts of potassium permanganate in 100 parts of water was added slowly, in the cold, to a solution containing 8 parts of lactic acid in 60 parts of water. After standing some hours the muddy solution was warmed to 70° C. when the suspended manganese dioxide gradually dissolved yielding, finally, a clear solution containing manganese and potassium pyruvates together with some unoxidised lactic acid. The latter was approximately neutralized with potassium carbonate. This solution was then incorporated into an aged tobacco which contained 3.75% nicotine and gave smoke tests of 8.5 S.A. and 11.7 T.S.B. The proportions used were such as to have in the tobacco 3% of manganese pyruvate with 2.5% mixed potassium pyruvate and lactate. The product gave smoke tests of 5.2 S.A. and 7.9 T.S.B.

(7) A shag tobacco in shredded form was tested and found to contain 4.4% nicotine and to give smoke tests of 7.0 S.A. and 10.2 T.S.B. The latter figure on further analysis was found to be made up of ammonia and easily volatile amines 7.04, nicotine 2.50 and pyridine-like bases 0.66.

This tobacco was then treated so as to incorporate into it 2% cobalt acetate, 2% magnesium acetate and 1% acetic acid. The product gave smoke tests of 1.4 S.A. and 5.0 T.S.B. the latter being divisible into ammonia bases 3.64, nicotine 0.96 and pyridine bases 0.40. The product was found to be very mild on smoking.

(8) Some flue-cured tobacco of a high stalk position was found to contain 4.4% nicotine and showed a S.A. of 9.9 and T.S.B. 13%. This tobacco was impossibly rank for smoking as such.

The leaves were sprayed with a solution containing invert sugar and magnesium acetate with precipitated manganese carbonate in suspension. The quantities used were such as to incorporate into the tobacco 8% of invert sugar, 2.0% magnesium acetate and 2.5% manganese carbonate. The finished product gave the very satisfactory tests of S.A. 3.0 and T.S.B. 8.5 and was found to be agreeably mild on smoking.

An American air-cured tobacco consisting of upper leaf (tips) was found to contain 1.65% nicotine and gave smoke tests of 11.4 S.A. and 15.4 T.S.B.

50

The leaves were sprayed with a solution of invert sugar and cobalt(ous) acetate. The quantities used were such as to incorporate into the tobacco 10% invert sugar and 2% cobalt(ous) acetate. The resulting product gave smoke tests of 5.3 S.A. and 8.9 T.S.B. A considerable improvement in quality was observed on smoking the product.

Obviously, modifications in the above described processes may be made without departing from the spirit and scope of this invention, as defined in the appended claims.

What is claimed is:

1. The process of treating normally discardable and poor quality portions of tobacco leaves to produce useful cigarette and pipe tobacco of high quality, comprising dispersing in said portions not more than approximately 2% by weight of a primary catalyst consisting of at least one suitable salt selected from the group of salts of the metals consisting of salts of cobalt, manganese, nickel, copper, chromium and silver, and introducing with said catalyst approximately 2% of a simple aliphatic acid selected from the group of suitable acids consisting of acetic, phosphoric, tartaric, glycollic and lactic acids.
2. The process of treating tobacco as defined in claim 1, including the step of adding approximately 10% of invert sugars, such as uncrystallizable syrups, molasses, honey and the like.
